UNITED STATES PATENT OFFICE.

LORENS C. LORENSON, OF HUDSON, NEW YORK, ASSIGNOR TO CLAYTON H. PETRY, OF HUDSON, NEW YORK.

BAGGING-MACHINE.

1,345,866.

Specification of Letters Patent.

Patented July 6, 1920.

Application filed May 24, 1918. Serial No. 236,337.

To all whom it may concern:

Be it known that I, LORENS C. LORENSON, a citizen of the United States, residing at Hudson, in the county of Columbia and 5 State of New York, have invented a new and useful Bagging-Machine, of which the following is a specification.

This invention has reference to bagging machines intended more particularly for 10 bagging coal and coke, and its object is to provide a machine of the weighing type which is, in the most part, automatic and requires but a minimum amount of attention by an operator.

15 The invention comprises a storage bin or hopper from which the coal or coke is fed intermittently into another hopper designed to deliver directly into a bag, the second hopper operating as an automatic weighing hopper which, when the predetermined amount of material is delivered into the 20 second hopper, will shut off further flow of material thereinto and deliver into the bag which may be taken as typical of any suitable 25 container but which will be hereinafter simply termed a bag without limitation to such particular container.

The invention includes various mechanisms of simple and inexpensive but durable 30 construction, which mechanisms are of a character to be reliable and certain in action.

The invention will be best understood from a consideration of the following detailed description taken in connection with 35 the accompanying drawings forming part of this specification, with the understanding, however, that the invention is not confined to any strict conformity with the showing of the drawings but may be changed and modified so long as such changes and modifications mark no material departure from the salient features of the invention as expressed in the appended claims.

In the drawings:

45 Figure 1 is a side elevation of the bagging machine.

Fig. 2 is a front elevation thereof.

Fig. 3 is a vertical front to rear section.

Fig. 4 is a section on the line 4—4 of

50 Fig. 1.

Fig. 5 is a section on the line 5—5 of Fig. 1, with parts in a different operative position, and distant parts being omitted.

Fig. 6 is a longitudinal section of the de-

livery spout showing a different adjustment 55 of the parts from that shown in Fig. 3.

Fig. 7 is a plan view of gates of the bagging hopper in the closed position, with the hopper omitted and the actuating levers for the gates shown in cross section.

Referring to the drawings, there is shown a main frame comprising two spaced columns 1, 2, which may be made of angle steel or in any other suitable manner and these columns are connected by a cross bar 3 and 60 are strengthened and stiffened by braces 4, 5 and connecting members 6 wherever needed. Secured to and supported by the upper ends of the columns 1 and 2 is a storage hopper 7 provided at the lower end 70 with a slanting spout 8 having a downturned extremity 9 for the discharge of the contents of the storage hopper. The spout has a top wall 10 provided with an angle portion 11 held against the corresponding wall of the 75 hopper 7 by clamp screws 12 extending through slots 13 in the angle extension 11 so that the wall 10 may be moved toward or from the bottom wall of the spout, thereby changing the effective cross sectional area 80 of the spout for conducting the material to be delivered through the spout. Within the spout is a gate 14 having a hinge connection 85 15 with the bottom of the spout, whereby the gate may be moved into closing relation to 90 the spout with the edge remote from the hinge engaging the adjustable top 10. The hinge 15 is exterior to the spout so that when the gate is open it forms a continuation of the bottom of the spout, which bottom is cut 95 away, as indicated at 16, to permit the gate to then aline with the bottom of the spout, thus avoiding any impediments to the free flow of material through the spout. Fast to the gate 14 on the side of its pivot or hinge 15 remote from the gate is an arm 17 provided with perforations 18 and this arm is connected by a bolt 19 or in any other suitable manner with a link 20 also provided with perforations 21 permitting adjustment 100 between the arm 17 and link 20. Fast to the columns 1 and 2 and extending therefrom on the side of the columns remote from the spout 8 are fixed supports 22, 23 respectively, and these supports are connected by a cross 105 beam 24 on which, about midway of its length, is erected a post 25 constituting a pivot support for a lever 26 having an arm

27 connected to the link 20 at the end of the latter remote from the arm 17.

Pivoted to the columns 1 and 2 by bolts 28 or otherwise are the legs of a U-frame 29 having a yoke portion 30 underriding the lever 26 and this yoke portion of the U-frame carries a counterweight 31. Hung from the free ends of the legs of the U-frame 29 is a bagging hopper 32, ears 33 fast to the hopper on opposite sides thereof being provided for the purpose. The hopper discharges through the lower end, which is the smaller end, the hopper being conical, and this discharge end is surrounded by a ring 34 fast to the hopper to accommodate the mouth of a bag. The discharge end of the hopper is traversed by oppositely movable gates 35 movable in guides 36 so that the gates may be approached to close the mouth of the hopper or moved away from each other to leave the mouth of the hopper free. Each gate is provided with ears 37 having a pin 38 thereon extending through an elongated slot 39 in one arm of a bell crank lever 40 having a pivot support 41 carried by brackets 42 on the outer face of the hopper 32. The arm 40 is expanded toward the slotted end thereby providing a slanting or angle edge 43. Carried by the cross bar 3 are spaced brackets 44 forming a pivot support for the yoke portion 45 of a U-shaped rod 46 of which latter the free ends of the legs are so disposed as to move along the slanting edges 43 of the bell crank levers 40 and also to engage the other arms of the bell crank levers, which arms are indicated at 47. Rocking movements of the U-rod 46 will cause corresponding rocking movements of the bell crank levers 40 by engaging the arms 40 as the rod 46 is moved in one direction and by engaging the arms 47 as the rod is moved in the opposite direction. The axis of rocking of the rod 46 is substantially horizontal so that when the free ends of the rod 46 are raised they engage the arms 47 of the bell crank levers 40 and rock these levers in a direction to separate the gates 35. When the rocking movement of the rod 46 is downward, the legs of the U-shaped rod move downwardly along the slanting edges 43 and cause the bell crank levers to rock toward each other in a manner to close the gates 35, thereby shutting off the outflow of any material in the hopper 32.

Pivoted to one of the braces 6 on one side of the main frame is a treadle lever 48, the pivot of the lever being conveniently in the form of a bolt 49 but of course may be otherwise formed. The lever 48 is provided at one end with a readily accessible treadle 50 and at the other end is connected by a rising link 51 to a bell crank lever 52 carried by the support 23. The bell crank lever 52 has an angle extremity 53 under-

riding one leg of the U-shaped frame 29. Adjacent to the pivot 49 on the side thereof remote from the treadle 50 the lever 48 has fast thereto another link 54 connected to one arm of the U-shaped rod 46.

That portion of the bottom of the hopper 7 leading toward the spout 8 has a screen section 55 for sifting out material sufficiently fine to pass through it, and in order to avoid undue scattering of such material, the screen section is underridden by a chute 56 directing the screenings into a narrow path and these screenings are prevented from interfering with an operator standing in front of the machine by a shield 57 extending between the columns 1 and 2 and dropping to near the bottom of the device, where a turned out portion 58 serves to direct the screenings away from the operator either onto the ground or floor or into a suitable receptacle. The treadle lever 48 may be held with the treadle lowered either by the foot of the operator or by a latch 59 adjacent to the treadle and in position to be readily disengaged by the foot of the operator. When the parts are in the position shown in Fig. 3, in which case the treadle end of the lever 48 is lowered, the other end of the lever 48 is raised and acts through the link 51 to rock the bell crank lever 52 in a direction to raise the weighted end of the U-frame 29 in opposition to the normal tendency of the counterweight 31. This movement causes the yoke portion 30 of the frame 29 to lift the corresponding end of the lever 26, thus lowering the link 20 and rocking the arm 17 in the direction to close the gate 14 so that any material in the hopper cannot at the time flow through the spout 8. At the same time the lowering of the treadle end of the lever 48 causes a raising of the free ends of the arms of the frame 46, thus bringing these arms into engagement with the arms 47 of the bell crank levers 40 and rocking the latter in a direction to open the gates 35. Therefore, the parts, as shown in Fig. 3, but before the treadle 50 is operated, are in position to have a bag applied to or located beneath the ring 34, and then, on pressing the treadle, coal or coke, or whatever material is in the hopper 32, is released to gravitate into a positioned bag or other receptacle beneath the hopper.

Now, when the hopper 32 has emptied, the release of the treadle end of the lever 48 either by relieving it from the pressure of the foot of the operator or by disengaging the latch 59, if utilized to hold the treadle end of the lever down, permits the counterweight 31 to become active to return the parts to the position shown in Fig. 1. The effect of the counterweight is to rock the frame 29 about its pivot supports 28 to raise the hopper 32 close to the mouth of

the spout 8 and directly beneath it. The raising of the treadle end of the lever 48 causes a lowering of the U-wire 46 which, moving along the slanting edges 43 of the levers 40, rocks the latter in directions to cause the closing of the gates 35. At the same time, the lever 26 is relieved from the restraining effect of the frame 29, whereupon, the gate 14 opens, both because of its own weight and the weight of the material bearing against it and tending always to open it. Now, the coal or coke has free outflow through the spout 8 and into the hopper 32 until the load is sufficient to overbalance the weight 31, whereupon, the hopper 32 drops to the position shown in Fig. 3 and then with the bag properly adjusted under the hopper the operator must press upon the treadle 50, thus raising the frame 46 sufficiently to cause the ends of the arms of the frame to engage the arms 47 of the bell crank levers 40 and open the gates 35 of the hopper 32 and discharge the contents of the latter. The dropping of the hopper 32 automatically causes the closing of the gate 14, thus shutting off further movement of the coal or coke into the hopper 32 until the latter is again raised.

What is claimed is:—

30 1. In a bagging machine, the combination with a spout and a weighing hopper thereunder having means for the application of a bag thereto, a gate for the spout in the line of travel of material therethrough and movable to open the spout, connections between the hopper and gate for closing the latter against the weight of material in the spout by the superior weight of the material delivered by the spout to the hopper, means for holding the gate closed while the bag is being applied to the hopper, and manually operable means located within ready reach of an operator for opening the gate to actuate the hopper and permit the latter to rise.

2. In a bagging machine, the combination with a spout of a weighing hopper having discharge means and located under the spout and movable under the weight of material deposited therein from the spout, of a gate for the spout, connections between the hopper and gate for closing the latter when the hopper is moved by the contained material, means for locking the hopper when moved under the weight of material therein, and means under the control of an operator for opening the hopper to discharge its contents and to release it to return to the receiving position when emptied.

60 3. In a bagging machine, a delivery spout, a bagging hopper arranged beneath the spout to receive material therefrom, a carrier for the hopper having means yieldable to the material in the hopper to permit the latter to drop under a predetermined

weight, a gate structure at the discharge end of the hopper, means for holding the hopper with its gate structure closed when the hopper drops under the predetermined weight of material, and means under the control of an operator for opening the gate structure to empty the hopper to return to the raised position ready to receive another charge of material.

4. In a bagging machine, a delivery spout, a rockable gate in the spout having an axis of rocking at one side of the spout for rocking the gate into the path of material passing through the spout, an arm on the gate exterior to the spout, link and lever connections with the arm, a bagging hopper in position to receive material from the spout, and a carrier for the hopper pivoted to rock about an approximately horizontal axis and having the end remote from the hopper in operative relation to the lever, whereby the gate is opened by rising movements and closed by lowering movements of the hopper, the last-named movements being against the weight of material back of the gate.

5. In a bagging machine, a spout, a bagging hopper located beneath the spout and having an up and down movement with relation to the spout, a gate within the spout movable into opening and closing relation thereto about an axis transverse of the spout, a pivoted U-shaped frame carrying the hopper and having a yoke portion remote from the hopper, and connections from the gate extended into the path of the yoke end of the U-shaped frame for engagement thereby on lowering movements of the hopper to cause the closing of the gate.

6. In a bagging machine, a bagging hopper, a rockable support therefor for up and down movements of the hopper, a counterweight on the support on the side of the axis of rocking remote from the hopper, a spout for directing material into the hopper, and means controlled by the rockable support for the hopper for in turn opening and closing the passageway through the spout.

7. In a bagging machine, a bagging hopper having an up and down movement, gates for the discharge end of the hopper movable into closing and opening relation thereto from opposite sides of the hopper, controlling bell crank levers connected to the gates and carried by the hopper with one arm of each lever having a slanting edge, and means in the path of both arms of each lever for causing the rocking of the levers to open and close the gates at the discharge end of the bagging hopper.

8. In a bagging machine, a bagging hopper, oppositely moving gates at the discharge end of the hopper for opening and closing the latter, bell crank levers, one for each gate and carried by the hopper with each

- lever having the adjacent edges at an acute angle one to the other, and means for acting upon the acute angular edges to cause rocking of the levers to open and close the 5 gates.
9. In a bagging machine, a bagging hopper, oppositely moving gates at the discharge end of the hopper for opening and closing the latter, bell crank levers, one for each 10 gate and carried by the hopper with each lever having the adjacent edges at an acute angle one to the other, and means for acting upon the acute angular edges to cause rocking of the levers to open and close the 15 gates, said means comprising a U-shaped rockable frame movable into engagement with the acutely related edges of the levers, and means for rocking the frame.
10. In a bagging machine, a bagging hopper, oppositely moving gates at the discharge end of the hopper for opening and closing the latter, bell crank levers, one for each 20 gate and carried by the hopper with each lever having the adjacent edges at an acute angle one to the other, and means for acting upon the acute angular edges to cause rocking of the levers to open and close the 25 gates, said means comprising a U-shaped rockable frame movable into engagement with the acutely related edges of the levers, and means for rocking the frame, said last 30 named means comprising a foot lever and connections between the latter and the U-shaped frame.
11. In a bagging machine, a spout for the delivery of material, a bagging hopper for receiving the material from the spout, a support for the bagging hopper for moving the latter up and down toward and from the 40 mouth of the spout, a gate in the spout, a lever connected to the gate and arranged in the path of the support for the bagging hopper, gates for the discharge end of the bagging hopper, a treadle lever and connections 45 therefrom for causing the opening and closing of the gates at the discharge end of the bagging hopper, means for engaging the support for the bagging hopper to hold the latter in the lowered position, and connections 50 between the treadle lever and the last named means for holding said last named means in position to maintain the bagging hopper in the lowered position.
12. In a bagging machine, a spout for the 55 delivery of material, a gate in the spout rockable about an axis transverse of the spout to close and open the latter, a bagging hopper located beneath the spout to receive therefrom, gates at the discharge end of the 60 bagging hopper and movable oppositely to

open and close the mouth end of the hopper, and means for causing the opening and closing of the gate in the spout and the closing and opening of the gates in the bagging hopper in alternation.

65

13. In a bagging machine, a spout for the delivery of material, a gate in the spout for controlling the delivery of the material therefrom, a rising and falling bagging hopper in position to receive from the spout, 70 closing and opening means for the delivery end of the bagging hopper, a rockable carrying means for the bagging hopper, means in the path of the carrying means for the bagging hopper for closing the gate in the spout, 75 a treadle lever, means under the control of the treadle lever for in turn controlling the opening and closing of the delivery end of the bagging hopper, and means under the control of the treadle lever for holding the 80 bagging hopper in the lowered position.

70

14. A machine for bagging material, comprising a frame, a storage hopper carried thereby at a high point, a discharge spout leading from the storage hopper, a bagging 85 hopper beneath the discharge spout, a rockable frame carrying the bagging hopper and pivoted to the main frame for rocking movements about a substantially horizontal axis, a counterweight for the bagging hopper on 90 the rockable frame, a gate in the spout, an operating lever for the gate connected thereto and in the path of the rockable supporting frame for the bagging hopper, oppositely slidable gates at the discharge end of 95 the bagging hopper, bell crank levers connected to the gates and carried by the bagging hopper, a rockable member carried by the main frame for in turn causing rocking of the bell crank levers to open and close 100 the gates connected thereto, a treadle lever, connections between the treadle lever and the rockable member carried by the main frame, a locking device for the rockable frame carrying the bagging hopper, and connections 105 between the treadle lever and said locking means.

100

15. In a bagging machine, a storage hopper provided with a screen section at its bottom portion, a chute underlying the screen 110 for receiving screenings, and a guard plate in the path of screenings discharged from the chute.

105

In testimony that I claim the foregoing as my own, I have hereto affixed my signature. 115
